FIG. 2

UNITED STATES PATENT OFFICE

2,516,839

EXHAUST HOOD

Raymond P. Allen, Jr., Essex, Fred D. Johnston, Towson, and William H. Sohn, Baltimore, Md., assignors to Western Electric Company, Incorporated, New York, N. Y., a corporation of New York

Application March 26, 1948, Serial No. 17,194

6 Claims. (Cl. 90—11)

1

This invention relates to exhaust hoods, and more particularly, to exhaust hoods for catching and carrying away chips from cutting machines.

In the use of cutting machines to cut away portions of articles, the chips which are normally formed must be cleaned away from the machine. Exhaust hoods have been proposed for carrying away such chips from cutting machines. In the past, exhaust hoods had to fit closely around the cutting elements of the machines to maintain sufficient air velocity to carry away the chips. Such close-fitting hoods seriously interfered with maintenance operations on the machines.

An object of the invention is to provide new and improved exhaust hoods.

Another object of the invention is to provide new and improved exhaust hoods for catching and carrying away chips from cutting machines.

A further object of the invention is to provide new and improved exhaust hoods loosely enclosing cutters during the operation of the cutters on work to permit access to the cutter and to remove effectively chips formed by the cutter.

An exhaust hood illustrating certain features of the invention may include a housing provided with a portion fitting over a rotary cutter and also having an opening therein to permit a work support to be moved into operative relationship with the cutter, said housing having a tapered portion facing in a direction designed to permit chips from the cutter to be thrown therein by the cutter, and means for creating a stream of air having a high velocity through the tapered portion of the housing to carry the chips through the smaller end thereof.

A complete understanding of the invention may be obtained from the following detailed description of an exhaust hood forming a specific embodiment thereof, when read in conjunction with the appended drawings, in which:

Fig. 1 is a vertical section of an apparatus including an exhaust hood forming one embodiment thereof;

Fig. 2 is a front elevation of the apparatus, and

Fig. 3 is a fragmentary, plan view of the apparatus.

Referring now in detail to the drawings, a bracket 10 secures a hood 12 to an overarm 14 of a milling machine, which includes a cutting spindle 16 having a cutter 18 mounted thereon, which rotates in a clockwise direction, as viewed in Fig. 1. A work carriage 20 may be slid from the left, as viewed in Fig. 1, to move work 22 through an opening 24 in the hood 12 into engagement with

2

the cutter 18, which cuts chips from the work and throws them toward a tapered portion 26 of the hood 12.

The hood 12 has an opening 28 at the bottom portion thereof to permit the carriage to be moved into working relationship with respect to the cutter 18, and to prevent chips from falling through the opening 28, a pan 30 secured to the carriage fits telescopically into the bottom portion of the hood and covers the opening 28 at all times that the cutter 18 is in engagement with the work.

A duct 32 connected to a restricted portion 34 of the tapered portion 26 is connected to a header 36 in which the pressure is substantially less than that of the atmosphere. The suction in the header 36 causes air to be drawn through the hood 12 and through the duct 32 at a very high velocity so that the chips, which are thrown toward the small end of the tapered portion 26 of the hood 12, are carried into the header from the hood 12. Part of the chips are carried by the air stream directly into the header and part fall on the pan 30 and the carriage. The chips falling on the pan and the carriage are picked up by the air stream travelling at a high velocity over the pan as the pan is moved toward the small end of the tapered portion of the hood. Since the tapered portion 26 of the hood 12 is mounted in facing relationship with respect to the chips from the work 22 as the chips are thrown by the cutter, a guard portion 37 of the hood 12 enclosing the cutter 18 may be very large. That is, the chips thrown by the cutter 18 are carried by the pan 30 and the carriage sufficiently far into the tapered portion 26 of the hood 12 to permit the stream of air flowing in the portion of the hood 12 adjacent to the cutter 18 to travel at a relatively low velocity, and the velocity of the air stream in the portion of the hood 12 over the pan 30 is high so that the chips are picked up and carried into the header.

The hood 12 is provided with a large opening 40 at an end of the spindle 16 so that after a plate 42 normally secured to the hood 12 over the opening 40 by wing nuts 44—44 is removed from the hood, the spindle 16 may be detached from the machine and withdrawn with the cutter thereon for sharpening the cutter or other maintenance operations without dismantling the hood from the machine. The portion of the hood immediately adjacent to the cutter 18 is substantially larger than the cutter 18. Hence, removal of the spindle of the machine is facilitated, and due to the position of the hood with respect to

the cutter, the exhaust function of the hood is not impaired by this large clearance.

A bracket 50 (Fig. 2) is secured adjustably to the bracket 10 by cap screws 52—52 which project through slots 54—54 formed in the bracket 50. A front cover 56 similarly is secured to the bracket 50 to increase the range of adjustment of the front cover with respect to the bracket 10 so that the cover 56 may always be positioned close to the top of the work throughout a wide variation in the height of work to be milled. The cover 50 increases the velocity of the air stream over the carriage and acts as a guard against injury from contact with the cutter 18.

Certain features of the exhaust hood 12 are disclosed and claimed in copending application Serial No. 17,195, filed March 26, 1948, by R. P. Allen, Jr. and W. H. Sohn, for "Exhaust Hoods."

What is claimed is:

1. In an apparatus including a milling cutter and means for moving work past the cutter, whereby the cutter cuts chips from the work, an improved exhaust hood, which comprises a tapered housing positioned with the large end thereof facing the cutter and adjacent thereto, said housing having an entrance portion positioned beyond the operative portion of the cutter to permit work moved past the cutter to enter the housing and move to a predetermined point therein intermediate the large and small ends of the housing, and means for forcing the air through the housing from the large end thereof to the small end thereof to remove chips from the work.

2. In an apparatus including a cutter and a work holder for moving a workpiece past the cutter so that the cutter cuts chips from the workpiece, an improved exhaust hood, which comprises a guard partially enclosing the cutter and having an adjustable covering on the approach side of the cutter for providing clearance for the workpiece, a housing in communication with the guard and having an entrance opening positioned beyond the operative portion of the cutter for permitting the work holder and the workpiece to be moved at least partially into the housing, and means for applying a low pressure head to the housing to draw air rapidly through the housing to remove chips from the work and the work holder.

3. In an apparatus including a cutter and a work holder for moving a workpiece past the cutter so that the cutter cuts chips from the workpiece, an improved exhaust hood, which comprises a guard partially enclosing the cutter and having an adjustable covering on the approach side of the cutter for fitting the workpiece closely and for providing clearance for the workpiece, a tapered housing in communication with the guard and provided with an opening in a wall thereof for permitting the work holder and the workpiece to be moved at least partially into the housing, a cover carried by the work holder for closing said opening, and means for applying a low pressure head to the housing to draw air rapidly through the housing to remove chips from the work and the work holder.

4. In an apparatus including a cutter and a work holder for moving a workpiece past the cutter so that the cutter cuts chips from the workpiece, an improved exhaust hood, which comprises a guard partially enclosing the cutter and having an adjustable plate on the approach side of the cutter, a tapered housing having the large end thereof in communication with the guard and also provided with a cutaway portion to permit the work holder to be moved into the housing, means for applying a low pressure head to the smaller end of the housing to draw air rapidly through the housing from the larger end thereof to the smaller end thereof, and a pan secured to the work holder and fitting telescopically with respect to the housing for keeping said opening in the housing covered.

5. In an apparatus including a spindle, a milling cutter and a work support reciprocable along a predetermined path for moving a workpiece past the cutter so that the cutter cuts chips from the workpiece, an improved exhaust hood, which comprises a tapered duct provided with a mouth of a predetermined height and a neck portion substantially less in height than the mouth mounted in alignment with the path of the work support, the mouth of the duct being nearer than the neck portion to the cutter, and a pan projecting from the work support into the duct and fitting telescopically into the duct for carrying chips toward the neck portion of the duct.

6. In an apparatus including a rotary tool and a work carriage movable from one side of the rotary tool to the other side thereof, the improved exhaust system which comprises a hood having a mouth and walls converging from the mouth to the other end thereof, the hood being so disposed that the mouth portion thereof substantially surrounds the tool and the portion of the hood having converging walls catches the chips cut from work by the tool, said hood having an opening extending from the mouth thereof toward the small end of the hood for providing clearance for the carriage and the work carried thereby, an exhaust tube connected to the small end of the hood for removing chips falling into the hood, and a sliding floor secured to the carriage closing the opening in the hood.
